(57) **CLAIM**

The ornamental design for an automobile, as shown and described.

DESCRIPTION

FIG. 1 is a perspective view of an automobile according to the present invention.

FIG. 2 is a front view of the automobile thereof.

FIG. 3 is a rear view of the automobile thereof.

FIG. 4 is a left side view of the automobile thereof.

FIG. 5 is a right side view of the automobile thereof; and, FIG. 6 is a top view of the automobile thereof.

A bottom view thereof is omitted since it does not contain ornamental features.
